G. FRÜBING

AUTOMATIC TELEPHONE EXCHANGE SYSTEM

Filed Sept. 1, 1921

UNITED STATES PATENT OFFICE.

GEORG FRÜBING, OF BERLIN-WILMERSDORF, GERMANY, ASSIGNOR TO SIEMENS & HALSKE AKTIENGESELLSCHAFT, OF WERNERWERK, SIEMENSSTADT, NEAR BERLIN, GERMANY.

AUTOMATIC TELEPHONE-EXCHANGE SYSTEM.

Application filed September 1, 1921. Serial No. 497,679.

(GRANTED UNDER THE PROVISIONS OF THE ACT OF MARCH 3, 1921, 41 STAT. L., 1313.)

To all whom it may concern:

Be it known that I, GEORG FRÜBING, a citizen of the German Empire, residing at Berlin-Wilmersdorf, Germany, have invented 5 certain new and useful Improvements in Automatic Telephone-Exchange Systems (for which I have filed applications in Germany, May 2, 1916, Pat. No. 299,512, and Austria, May 2, 1917, Pat. No. 80,904), of 10 which the following is a full, clear, concise, and exact description.

This invention relates to automatic telephone exchange systems and particularly to automatic telephone systems in which long 15 distance or toll connections are established by means of the same connector switches used in establishing connections between two local subscribers.

In order to make possible the use of the 20 same connectors for the local and toll traffic, it has been proposed to provide toll operator controlled switching means at the connector, in addition to the switching means controllable for the setting of the connector in 25 a local connection.

The drawback of such arrangement is that if the desired line, which is temporarily seized by the connector under the control of a toll operator, is idle, then, upon the seizure 30 of this line in response to this preparatory setting up of the toll connection, the desired line will be guarded against seizure. The temporary toll connection makes the desired line busy to local subscribers although this 35 line is not in actual use.

It has been proposed to test and guard the local lines under the control of switching apparatus associated with the connector and actuated at will under control of the toll 40 operator, rather than in response to the setting of the connector switch onto the terminals of the desired line. This arrangement, however, contemplated the use of switching means in addition to the switching means 45 associated with the connector for controlling its setting, and therefore increased the cost of operation.

It is the object of the present invention to provide a connector arrangement whereby a toll connection may be prepared for completion without seizing the called line, that is making it test busy, and in which the switching devices associated with the combination connector (for local and toll traffic) are reduced to a minimum.

According to the main feature of the invention, in response to the preparatory setting of a connector switch in a long distance connection, the guarding of the desired local line and also the further operations for completing the connection (testing of the desired line engaged in a local or toll connection, establishment of the talking circuit, supply of talking current, etc.), are operable under the control of the toll operator, 50 independently of operations performed during the setting of the connector. The circuits are so arranged that the toll operator when preparing the establishment of a connection, is first connected to the desired local subscriber in order to inform him of the long distance call if he is engaged in a local 55 connection.

The complete establishment of the toll connection may be accomplished under the 60 control of the toll operator in the same manner as the change-over from the vertical to the rotary motion of the switch is accomplished, or in the same manner as the connector is changed from local to long distance 65 use.

According to another feature of the invention, the complete establishment of a prepared toll connection is accomplished in response to the same operations as are performed upon the completed setting of a connector on a line in a local connection, whereby, in addition to the testing and guarding of a local line desired in a toll connection, the desired line may be signaled under the 70 control of the toll operator by the ringing arrangement associated with such connector, and at the same time an existing local connection may be severed.

In the drawings, Fig. 1 shows the circuits of the connector switch, arranged to be operated in a vertical and rotary direction, and Fig. 2 diagrammatically indicates a sending device such as may be employed by a toll operator.

C indicates the connector, T the test relay, SSM the side switch magnet, VM the vertical magnet, RM the rotary magnet, CR a connector release magnet, SSR a side switch release magnet, R the ringing relay, and I¹, I², I³ indicate interrupters. The side switch wipers controlled by the magnet SSM are numbered S^I, S^{II}, etc., S^{IX}. In order to simplify the circuits, the armatures of the various relays are not shown in their operative relations to such relays. The armatures of each relay are marked by a small letter corresponding to the capital designating the electromagnet of the relay. In order to distinguish between the various armatures of the same relay, suffixes are used in addition to the letters. The relay armatures are shown in their normal positions.

Setting of the connector in a local connection.

Upon the seizure of the trunk a, b, c leading to the wipers of the connector, relays A and B become energized in the well-known manner. Relay X does not become energized because it is differentially wound. Prior to the sending out of impulses for causing the connector to move in a vertical direction, the calling subscriber depresses keys K¹ and K², whereupon relay X becomes energized. Relay X closes contact x, thus closing a circuit from battery, x, the lower half of the left winding of B to ground. Relay B, being slow to release, does not fall off. Another circuit is closed from battery, through x, the upper half of the left winding of B, lower winding of X, conductor b and key K² to ground. The current which now flows through the lower winding of X is in a direction to assist that through the upper winding. The current flowing through the lower half of the left winding of B is greater than that through the upper half, and thus B remains energized. In order to send out the vertical impulses the calling subscriber operates key K¹ for operating relay A. Upon each deenergization, relay A closes a circuit from grounded battery, through a¹, a², VM, S^{VII} to ground. Under the control of the vertical magnet, the wipers of the connector are moved step by step in an upward direction. After the sending out of the last vertical impulse, the ground is disconnected from the a and b conductors, whereupon relay X becomes deenergized, and relays A and B remain energized. Upon the energization of relay X, a circuit was closed through armature x¹, the side

switch wiper S^{VII}, and magnet SSM to ground. The magnet SSM becomes energized, and upon the deenergization of relay X, the magnet becomes deenergized, and causes the movement of the side switch wipers out of position 1 into position 2. Prior to the sending out of the rotary impulses, the relay X is again energized as before. By operating key K¹ the subscriber causes the operation of relay A, but now due to the fact that side switch wiper S^{VII} is in its second position, the rotary magnet RM is operated instead of the vertical magnet, and under control of this magnet the wipers of the connector are rotated step by step. After the last rotary impulse has been sent out, relay X again becomes deenergized, and closes a circuit from grounded battery, through I¹, RON, x³, S^{VII}, SSM to ground.

The desired line is tested in position 2 of the side switch. The relay B, upon its energization, closes a circuit from ground through ON¹ for relay U, which becomes energized and closes a locking circuit for itself through contact u⁵. Off-normal contacts ON¹ open upon the first vertical step of the switch wipers. Relay U by closing its contact U⁶, prepares an energizing circuit for the I winding of relay R, which circuit is completed upon the deenergization of relay X. Relay R becomes energized, and closes its contacts r⁸ and r⁹ for preparing the ringing circuit. The relay R closes at its contact r¹⁰ a circuit for relay T, and if the line upon which the connector switch is set is idle, the test relay T becomes energized and closes its contacts t¹¹ and t¹², whereupon the ringing circuit is completed and the called subscriber is signaled. The circuit for relay T extends from ground through both windings in series, contacts r¹⁰, wiper S^V, and test brush, to contact 42, and thence to battery. Following testing, magnet SSM receives an impulse through interrupter I¹ and moves the side switch wipers into position 3. In this position of the side switch wipers, the winding II of the ringing relay R is connected to the interrupter I³, contact 13 of relay U being closed. The interrupter I³ is so arranged that the ringing relay is operated in intervals of ten seconds. Upon the removal of the receiver at the called station, and during a silent period of interrupter I³, relay Y becomes energized. This relay by closing its contacts 14, short-circuits the winding of relay U, which upon deenergization, opens at its contact u¹³ the circuit of winding II of the ringing relay.

The test relay when energized, short-circuits its high resistance winding I in its contact t²² and thus guards the called line from seizure by other connectors. The local connection is now completely established.

If the desired line is busy, then in position 3 of the side switch, the test relay has

not become energized, and the calling party is informed in the well-known manner of the busy condition of the desired line and hangs up his receiver. Relay B becomes deenergized and closes a circuit from ground through ON^2 , b^{17} , y^{18} , x^{21} , SSR, to grounded battery. Under the control of SSR, the side switch wipers are returned to normal, and when side switch wiper S^{VIII} reaches its normal position and closes contacts SC, magnet CR becomes energized and causes the release of the connector. When the connector reaches its normal position, contact ON^2 is opened and magnets SSR and CR become deenergized.

If after the complete establishment of the connection the desired subscriber restores his receiver to the switchhook, the relay Y becomes deenergized, and connects interrupter I^2 in circuit with the magnet SSM. Upon the energization and subsequent deenergization of the magnet SSM, the side switch wipers are moved into position 4. While the side switch wipers are moving from position 3 to 4 and in position 4, the relay T remains energized. The holding circuit of relay T may be traced from grounded battery through resistance 4, S^{IX} , T^H , to ground. A circuit is therefore closed through the test conductor c , S^I (position 4), t^{19} , u^{20} and conductor a for causing the operation of the calling subscriber's register (not shown). The circuit closed to actuate the register, also causes the release of the selector by means of which the calling line has been extended to the connector, whereupon relays A and B become deenergized. The above described circuit is then established for SSR and CR for releasing the side switch and the connector.

If the calling subscriber hangs up his receiver after a successful connection has been established, then the above described register circuit is completed from conductor c , through armature b^{22} of the relay B, whereupon in response to the restoration of the receiver at the called substation and the subsequent deenergization of relay Y, the side switch and the connector are released in the above described manner.

Setting of the connector in a toll connection.

The connector is moved in a vertical and rotary direction for seizing the desired local line in the same manner as above described and is under the control of a toll operator whose sender comprises keys (Fig. 2) similar to those of a local subscriber. After the last rotary impulse has been sent out, the relay B becomes temporarily deenergized, due to the connection of an opposing battery connection to the b conductor at the sending station, as by means of a key K^3 . Relays A and X remain energized. The following circuit is now established: grounded

battery, b^{26} , a^{27} , S^H (position 2), relay V, to ground. Relay V becomes energized and closes a locking circuit for itself through its armature V^{29} and the armature a^{30} of relay A. In response to the temporary deenergization of relay B, relay U also becomes deenergized. Due to the fact, however, that relay X is energized and maintains its armature x^{21} attracted, the release magnets of the side switch and the connector are not operated.

The toll operator now causes the relay X to restore its armatures and relay B to pull up its armature, relay A being maintained operated. The magnet SSM receives an impulse through interrupter I^1 and the armature x^8 of relay X, and causes the movement of the side switch wipers out of position 2 and into position 3 in the above described manner. In this position of the side switch wipers, the line on the terminals of which the connector has been set is neither tested nor guarded, because relay U maintains the circuits of relay R open (in u^6 and u^{19}), and relay R in turn maintains the test circuit open (in r^{10}). The connector remains in the set position until further operated under the control of the toll operator. Thus the connector is set to prepare a toll connection.

As soon as the toll operator decides to complete the toll connection, she will cause the temporary deenergization of relay B and the energization of relay X, as by operating keys K^1 and K^3 (Fig. 2). The toll operator causes the energization of relay X by depressing key K^1 as previously described, and by operating key K^3 , connects an opposing battery to the b conductor which causes the B relay to become temporarily deenergized. In response to the short deenergization of the relay B, the magnet SSM becomes energized and deenergized and moves the side switch wipers into position 4. The circuit may be traced as follows: from grounded battery by way of b^{26} and its resting contact, a^{27} and its working contact, side switch wiper S^H in third position, side switch wiper S^{VI} in third position thru side switch magnet SSM to ground. The called line is now tested.

If the called line is engaged in a toll connection, the test relay T is short-circuited through a connector holding the called line, the side switch wipers of this connector being in position 8. The magnet SSM is operated by interrupter I^2 , the contact v^{33} of relay V being closed. The side switch wipers then move into position 5, and in view of the fact that relay T is not energized, a circuit is closed from ground through the secondary winding of a toll busy signal, S^{VIII} (position 5), armature v^{34} of relay V, armature t^{35} of relay T and coils 36 and 37 to ground. The toll op-

erator receives a busy tone, and either releases the connector or leaves it in the set position until the called line becomes idle.

If the desired line is idle, relay T becomes energized when the side switch wipers move into position 4, the circuit being closed from grounded battery, through resistance 4, S^{IX} (position 4), T^{II} to ground. The magnet SSM receives an impulse through v³³ and moves the side switch wipers into position 5. While the side switch wipers are moving from position 4 to 5, and in position 5 of these wipers, the relay T is maintained energized by current flowing in the following circuit: grounded battery, resistance 4, S^{IX} (position 5), v⁴¹, t²², T^{II}, to ground. At the same time a busy potential is connected to the test terminal 42 of the called line through a resistance 3 and S^V (position 5).

If the desired subscriber is engaged in conversation with a local subscriber, then upon the completed setting of the connector under the control of a toll operator and the movement of the side switch wipers into position 4, relay B being temporarily de-energized, relay T becomes energized. The circuit extends from grounded battery through resistance 4, S^{IX} (position 4), T^{II}, ground. The magnet SSM then receives an impulse through I² and v³³, and causes the movement of the side switch wipers into position 5. The toll operator now hears the conversation on the line and understands thereby that the called subscriber is engaged in a local conversation. The toll operator then informs him of the incoming toll call and the impending severance of the local connection. The toll operator then again causes the temporary de-energization of relay B. A circuit is now closed from grounded battery, through b²⁶, a²⁷, S^{II} (position 5), S^{VI} (position 5), SSM, ground, and upon the subsequent energization of relay B, the magnet SSM causes the side switch wipers to move into position 6. In this position of the side switch, a circuit is closed through I², v³³, b⁴⁴ and S^{VI} for the magnet SSM, and the side switch wipers are moved into position 7. The side switch wiper S^{III} now connects a ten-volt battery to the a conductor of the local connection, and side switch wiper S^{IV} a ground to the b conductor of the local connection. In response to this, the local connection is severed in the well-known manner, as described in British Patent No. 2,672 of 1912. If the desired subscriber was the calling party of the local connection, then his line switch is released, and if he was the desired party in the local connection, the connector of that connection is released. Battery is then supplied through test terminal 42, side switch S^V and conductor 48 to the II winding of relay Y. This relay becomes energized and attracts

its armature Y⁴⁰. The interrupter I² is then connected to the magnet SM, and the latter causes the movement of the side switch wipers into position 8. If the desired subscriber has replaced his receiver, relay Y will be deenergized. The toll operator may then cause the signaling of the desired substation. By temporarily de-energizing relay B and energizing relay X, the operator may cause the establishment of a circuit for the ringing relay from grounded battery, through b²⁶, a²⁷, S^{II}, R¹, y⁵¹, to ground. When the called subscriber removes his receiver from the switchhook, the relay Y is energized by a circuit including the conductors a and b in series.

The toll connection is now completely established.

After the completion of the conversation, when the desired party hangs up his receiver, relay Y becomes deenergized, and the toll operator's clearing-out signal is actuated, whereupon she causes the severing of the connection, by the removal of her cord circuit from the jack in which the conductors a, b, and c terminate. Relay B becomes deenergized and in the same manner as above described, causes the energization of the magnets SSR and CR for releasing the side switch and the connector.

What is claimed is:

1. In a telephone exchange system, a connector switch having movable and stationary contacts, toll lines arranged for connection to said movable contacts, local lines terminating in said stationary contacts and arranged for connection to said movable contacts, means operable through any one of said lines for causing said connector to move its movable contacts on to the stationary contacts of a desired line, automatic testing means associated with said connector for testing the busy or idle condition of the desired line, automatic guarding means associated with said connector for making the line connected with busy, automatic switching means operable in response to the setting of said connector over a local line for operating said testing and guarding means, means controllable through a toll line in making connection with the desired line for preventing the operation of said testing and guarding means so that said desired line will not test busy to other switches, and a manually operable switch operated at will for controlling the operation of said testing and guarding means through a toll line to guard against seizure of said desired line by other switches.

2. In a telephone system, connector switches having movable and stationary contacts, toll lines arranged for connection to said movable contacts, local lines terminating in said stationary contacts and arranged for connection to said movable contacts.

- 5 contacts, means operable by any one of said local lines for causing one of said connector switches to move its movable contacts on to the stationary contacts of a desired line and to automatically make said line test busy to other subscribers, means operable through one of said toll lines for connecting with the stationary terminals of a desired line whether said line is busy or not, means for maintaining said last mentioned connection without making said line test busy to other connector switches having access thereto, and means thereafter controlled at will by the operator for completing telephonic connection with said desired line and for making said line busy to other connector switches having access thereto.
- 20 3. In a telephone system, a connector switch having movable and stationary contacts, toll lines arranged for connection to said movable contacts, means operable through any one of said lines for causing said connector to move its movable contacts on to the stationary contacts of a desired line, means for connecting with the stationary terminals of a desired line whether said line is busy or not, and means effective if the line is idle for maintaining said last mentioned connection and for preventing said connector from making said line test busy to other connector switches having access thereto.
- 25 4. In a telephone system, a connector switch having movable and stationary contacts, toll lines arranged for connection to said movable contacts, means operable through any one of said lines for causing said connector to move its movable contacts on to the stationary contacts of a desired line, means for connecting with the stationary terminals of a desired line whether said line is busy or not, means for maintaining said last mentioned connection without making said line test busy to other connector switches having access thereto, and means thereafter controlled at will by the operator for completing telephonic connection with said desired line and making the same busy to other connector switches having access thereto.
- 30 5. In a telephone system, a toll connector directly controlled by an operator for selecting a desired line, means in said connector for testing the selected line, means for preventing the operation of said testing means when the line is selected, and operator controlled means for causing the testing operation to take place at any desired time thereafter.
- 35 6. In a telephone system, a toll connector directly controlled by an operator for selecting a desired line, means in said connector for making the selected line busy in case it is idle when selected, and means for preventing the operation of said busying means while maintaining the connector in operated selective position.
- 40 7. In a telephone system, a toll connector directly controlled by an operator for selecting a desired line, means in said connector for testing the selected line, means for preventing the operation of said testing means when the line is selected, operator controlled means for causing the testing operation to take place at any desired time thereafter, and means effective in case the line is found busy for completing or barring the connection depending on whether the selected line is busy in a local connection or in a toll connection.
- 45 8. In a telephone system, a combination toll and local connector for use by an operator or by local subscribers in selecting and connecting with called lines, means in said connector for testing a called line as soon as selected in case the connector is in use by a local subscriber, and means for delaying the testing operation in case the connector is in use by the operator.
- 50 9. In a telephone system, a combination toll and local connector for use by an operator or by local subscribers in selecting and connecting with called lines, means in said connector effective automatically to make an idle called line busy as soon as the same is selected in case the connector is in use by a local subscriber, and means whereby in case the said connector is in use by the operator an idle called line is made busy at the will of the operator.
- 55 10. In a telephone system, a combination toll and local connector for use by an operator or by local subscribers in selecting and connecting with called lines, and busy testing means in said connector operable automatically or at the option of the calling party depending on whether said connector is being used by a local subscriber or by the operator.
- 60 11. In a telephone system, a combination toll and local connector for use by an operator or by local subscribers in selecting and connecting with called lines, a multi-position switching device in said connector, a test circuit closed in one position of said device if the connector is in use by a local subscriber and closed in a different position if said connector is in use by the operator.
- 65 12. In an automatic telephone system, an automatic switch controlled by an operator for selecting a subscriber's line, a key at the operator's switchboard, and means in said switch requiring two successive actuations of said key to signal the called subscriber.
- 70 13. In an automatic telephone system, an automatic connector switch controlled by an operator for selecting a subscriber's line, said line remaining in idle condition, means controlled by the operator at will for mak-
- 75 80 85 90 95 100 105 110 115 120 125 130

ing said line busy, and additional means thereafter controlled by the operator at will for signalling the called subscriber.

14. In an automatic telephone system, an automatic connector switch controlled by an operator for selecting a subscriber's line, said line remaining in idle condition, and

means controlled by the operator at will for making said line busy and ringing the called subscriber.

In witness whereof, I hereunto subscribe my name.

GEORG FRÜBING.
